TIRE

Arthur C. Blankenship, Detroit, Mich., assignor to United States Rubber Company, New York, N.Y., a corporation of New Jersey

Filed Sept. 28, 1964, Ser. No. 81,904

Term of patent 14 years

(Cl. D90—20)

Fig. 1

Fig. 2

Fig. 3

FIG. 1 is a perspective view of a tire embodying my new design, it being understood that the full line portion is repeated throughout the circumference of the tire, shown by means of broken lines;

FIG. 2 is an enlarged fragmentary plan view of the tread portion of the tire shown in FIG. 1, and

FIG. 3 is a fragmentary sectional view taken substantially on the plane indicated by line III-III of FIG. 2, but on a smaller scale than FIG. 2.

The dominant features of my design reside in those portions of the tire shown in full lines in the drawings.

I claim:

The ornamental design for a tire, substantially as shown and described.
